UNITED STATES PATENT OFFICE.

TRAVILLA C. GETTELL, OF PHILADELPHIA, PENNSYLVANIA, ASSIGNOR OF ONE-HALF TO FREDERICK LAMBDEN, OF BALTIMORE, MARYLAND.

BURGLAR-DETECTIVE APPARATUS.

Application filed January 26, 1921. Serial No. 440,045.

To all whom it may concern:

Be it known that I, TRAVILLA C. GETTELL, a citizen of the United States, residing in the city of Philadelphia, county of Philadelphia, and State of Pennsylvania, have invented certain new and useful Improvements in Burglar-Detective Apparatus, of which the following is a specification.

My invention is a burglar detective apparatus adapted for use in conjunction with a show window and comprises a curtain therefor and means whereby, when the glass is broken, electric circuits are closed, an alarm is sounded, and the curtain is lowered and charged with static electricity adapted for shocking and holding one coming in contact therewith.

The nature and characteristic features of the invention are fully set forth in the following description and the accompanying drawings in illustration thereof.

In the drawings, Fig. 1 is a broken vertical sectional view taken through a window equipped with my improvements; Fig. 2 is a sectional view taken on the line 2^x—2^x of Fig. 1; and Fig. 3 is a diagrammatic view in illustration of the invention.

As shown in the drawings, my invention is applied to a window comprising a frame 1 and glass 2. In the form of the invention illustrated in the drawings, a roller 3, journaled in brackets 4 fixed to the frame adjacent to the top of the window has rolled thereon a curtain 5, comprising conducting material as tin foil, which is connected by cords 6 with a roller 7 journaled in brackets 8 fixed to the frame adjacent to the bottom of the window.

The rollers 3 and 7 are provided with the similarly acting springs 9 and 9' tending to draw the curtain 5 down over the window, the curtain being normally held rolled up and the springs under tension by the engagement of the radial finger 10 with the armature 11 of an electromagnet 12.

A bent rod 13 of conducting material is seated in the conducting bearings 14 and has thereon the rubber or cork cushions 15 bearing against the glass 2, whereby the conducting rod is normally held out of engagement with the contacts 16 on opposite sides of the window.

A source of electric energy as the battery 17, has one of its poles connected with the bearings 14 through the conductor 18, (hav-

ing in its circuit the coil of the electromagnet 12), and the branch conductors 18¹ and 18¹¹. The other pole of the battery is connected with the terminals 16 through a conductor 19 (having in its circuit a switch lock 20) and the branch conductors 19¹ and 19¹¹. A branch conductor 21 tapped off the conductor 18 is connected with a bell 22; a conductor 23 connecting the bell with the core 24 of an electromagnet 25. This core is connected through the conductors 26 and 27 with the coil of the electromagnet 25 and therethrough and the conductor 28 with the conductor 18. The core is also connected by the conductors 26 and 29 with the branch conductor 18¹¹. The armature 30 of the electromagnet 25 is connected with the conductor 19.

A second source of electric energy, as the battery 31, has one of its poles connected by the conductor 32 with the core 33 of the armature 12, and its other pole connected by the conductor 34 with the armature 11, the conductor 34 having in its circuit the shocking vibrator 35. A branch conductor 36 connects the conductor 34 with the conducting bracket 4 and therethrough with the roller 3 and curtain 5. A terminal of the secondary coil of the shocking vibrator 35 is connected by a conductor 37 with the ground and by a branch 38 with the layer of tin foil 39 on the window sill or floor adjacent to the window.

In the operation of my apparatus, all of the circuits are normally open, but when the conducting bar 13 is disturbed, as by the breaking of the window, the bar is brought into contact with one of the adjacent terminals 16 and current flows from the positive pole to the battery through conductor 18, electro-magnetic coil 12, branch conductors 18¹ and 18¹¹, bearings 14, rod 13, terminals 16, branch conductors 19¹ and 19¹¹, switch lock 20 and conductor 19 to the negative pole of the battery. Current also flows from the positive pole of the battery through the conductor 21, bell 22, conductor 23, core 24, conductors 26 and 27, coil 25 and conductor 28, and through the conductors 29 and 18¹¹ to the conductor 18 which is connected through the circuit above described with the negative pole of the battery, whereby the bell is operated and the electro-magnet 25 is excited. The excitation of the electro-magnet 25 draws thereto

the armature 30, whereby a shunt circuit is established, and current flowing from the conductor 18 through the coil 25, conductors 27 and 26, core 24, armature 30 and conductor 19 to the negative pole of the battery maintains the magnetization of the electro-magnet 25 and current flowing through the conductor 21, bell 22, conductor 23, core 24, armature 30 and conductor 19 continues the operation of the bell even though the contact between the rod 13 and the contacts 16 be broken. A portion of the current flowing in the conductor 18 also passes through the electro-magnet 12, branch conductor 18¹¹, conductors 29 and 26 to the core 24 and thence to the negative pole of the battery, thereby maintaining closed the circuit of the battery 31 in the event the rod 13 is disconnected from the contact 16.

20 The flow of current through the conductor 18 energizes the electro-magnet 12 which draws up the armature 11 out of engagement with the finger 10, whereby the rollers 3 and 7 are released and the curtain quickly

25 drawn across the window by the unwinding of the springs 9 and 9'. The engagement of the armature 11 with the core of the electro-magnet 12 closes the circuit of the battery 31 through the shocking vibrator 35, which is thereby operated and discharges electricity through the branch conductor 36 bracket 4, roller 3 to the curtain 5, and through the conductor 37 to ground and through the conductor 38 to the tin foil 39. Consequently when an intruder touches the charged curtain the circuit of the vibrator is closed through the tin foil, or ground, and the intruder receives a severe shock and is held fast to the curtain.

40 Having described my invention, I claim:

1. In a protective system of the character described, the combination with a closure, of a curtain, means for operating said curtain, and mechanism comprising an automatically movable device normally restrained from movement by said closure for

rendering said operating means inoperative.

2. In a protective system of the character described, the combination with a closure, of a curtain, means for automatically moving said curtain, and electro-magnetic mechanism for controlling said means and comprising a circuit normally held open by the engagement of a member thereof with said closure.

3. In a protective system of the character described, the combination with a sheet of material, of a curtain, means for automatically operating said curtain, electro-magnetic mechanism for controlling said means and comprising a circuit containing a movable contact member adapted to be actuated by the disturbance of said sheet of material, and means for electrically charging said curtain.

4. In a protective system of the character described, the combination with a closure, of a curtain comprising conducting material, and means comprising a device actuated by the disturbance of said closure for electrically charging said curtain.

5. The combination with a closure, of a protective system comprising an electric circuit and means for controlling it and a second circuit controlled by said first named circuit and comprising a shocking vibrator, normally disconnected conductors electrically connected with said vibrator, and a member adjacent to said closure to which electricity is discharged when said last named conductors are connected.

6. In a protective system of the character described, an electric circuit containing electro-magnetic mechanism, means for controlling said circuit, a second circuit controlled by said electro-magnetic mechanism and containing a shocking vibrator, and a conducting curtain, connected with said vibrator.

In testimony whereof I have hereunto set my name this 24th day of January, 1921.

TRAVILLA C. GETTELL.
